UNITED STATES PATENT OFFICE.

ALBERT GRAN, OF CHICAGO, ILLINOIS, ASSIGNOR TO DESIGNERS INSTRUMENT COMPANY, OF CHICAGO, ILLINOIS, A CORPORATION OF ILLINOIS.

FOUNTAIN RULING-PEN.

1,355,961.

Specification of Letters Patent. Patented Oct. 19, 1920.

Application filed December 20, 1919. Serial No. 346,232.

To all whom it may concern:

Be it known that I, ALBERT GRAN, a citizen of the United States, residing at Chicago, in the county of Cook and State of Illinois, have invented new and useful Improvements in Fountain Ruling-Pens, of which the following is a specification.

This invention relates to improvements in pens and refers more particularly to fountain ruling pens.

The principal object of the invention is to provide a simple and effective ruling pen of the foregoing type having a reservoir for ink and means for delivering ink from the reservoir to the pen blades when desired.

A further object is to provide such a pen with means for regulating the amount of ink to be applied to the pen blades from the reservoir, together with a safety device whereby the feed of ink may be entirely cut off when the pen is not in use.

With the foregoing and other objects in view, the invention comprises the new and useful details of construction and arrangement, which will be fully described herein, illustrated in the annexed drawings and claimed more specifically hereinafter.

In the drawings,

Figure 1 is a side elevation of a fountain ruling pen embodying the improvements of this invention, and Fig. 2 is a longitudinal sectional view of the improved ruling pen.

Referring now to the drawings, it will be seen that the improved ruling pen comprises a hollow handle or barrel 1, which forms an elongated reservoir 2 for the reception of a supply of ink, the ends of the barrel being internally threaded to receive a pen socket 3 at the lower end and a top 4 at the other end. Into the outer end of pen socket 3 is screwed the base of the pen blades 4^a which are preferably of the integral type having a threaded cylindrical base 5. The blades are adjustable for width of line by an adjusting screw stem 7 and nut 9 in the usual manner.

Pen socket 3 and base 5 of the pen blades are bored out longitudinally to receive a fixed feed tube 6, which tube is restricted in diameter at its lower end where it passes through an enlargement 8 of the screw stem 7 between the blades of the pen, the part 8 being perforated longitudinally of the pen to receive the feed tube. Within feed tube

6, and slidable therein, is a pointed needle valve 10 which is grooved longitudinally as at 10^a for a purpose to be presently explained.

The upper end of needle valve 10 is enlarged to form a plunger head 11 and the inner end of pen base socket 3 is elongated and centrally bored to form a plunger chamber 12 in which the plunger head is adapted to move longitudinally, the chamber being radially perforated at 12^a to provide an inlet port for ink from the reservoir 2. Plunger head 11 has a collar 13 formed on its outer end and a coil spring 14 has one end seated against the collar 13 and the other end seated against a washer 15 abutting against the inner end of pen socket 3, the spring being carried about the plunger head in position to normally retract the plunger and close the needle valve.

The top 4 is centrally bored to receive an axial plunger rod 16, the inner face of the top being counter bored to form a packing chamber 17 and internally threaded to receive a suitable centrally perforated packing nut 18. Rod 16 is threaded below the inner face of packing nut 18 and a nut or sleeve 19 is carried thereon to provide an adjustable seat or abutment for one end of the coil spring 20 on rod 16, the other end of said spring seating against the packing nut, the spring thus being positioned to normally urge plunger rod 16 downward into contact with the upper end of plunger head 11. The upper end of plunger rod 16 is provided with a fixed recess cap 21, the cap being positioned to slide longitudinally and also rotate on the top 4 with the plunger rod.

The operation of filling reservoir 2 may be effected by unscrewing top 4 from barrel 1 and withdrawing the top and plunger rod therewith, whereupon ink may be introduced to the reservoir in any suitable manner, as by an ink dropper. The top and accompanying parts may then be screwed into place, an air vent groove 22 allowing the displaced air within the reservoir to escape.

The filling of the pen blades is accomplished by the actuation of cap 21 and plunger rod 16 downward, whereupon the plunger head 11 will also be forced downward against the normal action of coil spring 14, the ink within chamber 12 being forced

downward into tube 6 about needle valve 10. When the needle valve has traveled downward sufficiently, the grooved portion 10a thereof will reach the end of the feed tube, thereby providing an outlet port through which the ink may flow downward about the pointed end of the needle valve and allowed to collect between the blades of the pen in the usual manner.

10 The amount of ink to be deposited between the pen blades is regulated by a device for adjusting the length of stroke of plunger rod 16, plunger head 11 and needle valve 10. Cap 21 is provided with a plurality of longitudinal slots such as 23, 24 and 25, and the top 4 is provided with a projecting spline 26 in position to engage such slots selectively. When it is desired to deposit a relatively large amount of ink between the pen blades with each stroke of the feed mechanism, the cap may be slightly withdrawn from the top against the normal action of spring 20 and then rotated on top 4 so that the spline 26 will engage in slot 23.

15 25 The pen is then set for delivering the relatively large quantity of ink at each stroke, since the plunger head and needle valve will travel downward substantially the full stroke. When spline 26 is engaged in slot 30 24, a shorter stroke will be attained by reason of the relatively shorter travel allowed by slot 24, the stroke being limited by the contact of spline 26 and the end of the slot. When spline 26 is engaged in slot 25 no 35 downward stroke of the feed device will be possible, thus locking the feed device entirely; this position is obviously desirable when the pen is out of use, thus preventing accidental actuation in handling.

40 45 From the foregoing description it will be apparent that the present invention provides a simple and effective ruling pen having a reservoir for ink, and that improved means are applied thereto for feeding ink to the pen blades in desired quantities and for locking the feed device when the pen is out of use.

I claim:

1. A ruling pen comprising a hollow handle forming an ink reservoir, a removable closure for one end of the handle, pen blades carried by the other end of the handle, an ink feed tube extending from the reservoir and terminating between the pen blades, a longitudinally slidable plunger head in the feed tube positioned to force ink through the feed tube, a needle valve carried by the plunger in position to normally close the feed tube and having a groove therein positioned to open the feed tube upon advance of the plunger and needle valve, and a plun-

ger rod in operative engagement with the plunger head.

2. A ruling pen comprising a hollow handle forming an ink reservoir, a removable closure for one end of the handle, pen blades carried by the other end of the handle, an ink feed tube extending from the reservoir and terminating between the pen blades, a longitudinally slidable plunger head in the feed tube positioned to force ink through the feed tube, spring means carried by the feed tube and the plunger in position to normally retract the plunger, a needle valve carried by the plunger in position to normally close the feed tube and having a groove therein positioned to open the feed tube upon advance of the plunger and needle valve, a plunger rod carried centrally of the handle and projecting through the aforesaid closure, and spring means carried by the closure and plunger rod in position to normally actuate the plunger rod forward into contact with the plunger head.

3. A ruling pen comprising a hollow handle forming an ink reservoir, a removable closure for one end of the handle, pen blades carried by the other end of the handle, an ink feed tube extending from the reservoir and terminating between the pen blades, a longitudinally slidable plunger head in the feed tube positioned to force ink through the feed tube, the feed tube being radially perforated adjacent to the normal position of the face of the plunger head to allow ink from the reservoir to enter the feed tube, a needle valve carried by the plunger in position to normally close the feed tube and having a groove therein positioned to open the feed tube upon advance of the plunger and needle valve, a plunger rod in operative engagement with the plunger head, and a recessed cap fixed to the plunger rod to slide on the aforesaid closure and having stroke limiting slots in its wall, and the closure having a projecting spline positioned to be engaged selectively in the stroke limiting slots in the cap.

4. A ruling pen comprising a hollow handle forming an ink reservoir, a removable closure for one end of the handle, pen blades carried by the other end of the handle, an ink feed tube extending from the reservoir and terminating between the pen blades, a longitudinally slidable plunger head in the feed tube positioned to force ink through the feed tube, a valve carried by the plunger for controlling the discharge from the feed tube, and operating means for the plunger head.

In testimony whereof I affix my signature.

ALBERT GRAN.
